Primary Examiner — Leanne Was-Englehart(74) *Attorney, Agent, or Firm* — Berenato & White, LLC**CLAIM**

The ornamental design for a lite, as shown and described.

DESCRIPTION

FIG. 1 is a front plan view of our design, with the rear view being a mirror image; and,

FIG. 2 is a perspective view of FIG. 1.

Broken lines indicate boundaries that form no part of the claimed design.
